UNITED STATES PATENT OFFICE.

IRA L. STELL, OF SHERMAN, TEXAS.

FERTILIZER-DISTRIBUTER.

SPECIFICATION forming part of Letters Patent No. 636,079, dated October 31, 1899.

Application filed June 19, 1899. Serial No. 721,136. (No model.)

To all whom it may concern:

Be it known that I, IRA L. STELL, a citizen of the United States, residing at Sherman, in the county of Grayson and State of Texas, 5 have invented a new and useful Fertilizer-Distributer, of which the following is a specification.

The invention relates to improvements in fertilizer-distributers.

10 The object of the present invention is to improve the construction of fertilizer-distributers and to provide a simple and comparatively inexpensive one adapted for handling all kinds of fertilizers—such as manure, straw, 15 and analogous accumulations, wood-ashes, and the like—and capable of positively feeding the same and of depositing the material in drills or furrows.

20 A further object of the invention is to enable the cutting knives or arms for operating on the material to be readily removed when it is necessary to sharpen them.

25 The invention consists in the construction and novel combination and arrangement of parts hereinafter fully described, illustrated in the accompanying drawings, and pointed out in the claims hereto appended.

30 In the drawings, Figure 1 is a perspective view of a fertilizer-distributer constructed in accordance with this invention. Fig. 2 is a longitudinal sectional view of the same. Fig. 3 is a detail sectional view illustrating the manner of mounting the cutter blades or arms. Fig. 4 is a detail perspective view of 35 one of the cutter-blades.

Like numerals of reference designate corresponding parts in all the figures of the drawings.

40 1 designates a hopper mounted upon a frame 2, which is rectangular and provided at its corners with vertical standards 3, secured at their upper ends to the corners of the hopper, at the top thereof. The frame, which is composed of side and end bars, is supported by transverse bars 4 and 5, located in advance and in rear of a centrally-arranged axle 6, which is journaled in suitable bearings 7 and which has carrying-wheels journaled on its spindles. A draft beam or tongue 45 7^a is secured to the front of the frame, and its rear end is supported by the transverse bar 4. The carrying-wheels 7^b are connected

with the ends of the axle by clutches, composed of ratchet-wheels 8 and pawls 9. The ratchet-wheels are mounted on the shaft, and 55 the pawls 9, which are pivoted to the inner face of the carrying-wheels, are adapted to be swung out of engagement with the ratchet-wheels, whereby the machine may be thrown 60 into and out of operation.

The axle is provided with centrally-arranged transverse perforations 10, disposed at right angles to each other and receiving bars 11, and each bar 11 projects from opposite sides of the shaft to form arms, which are adapted 65 to operate through an opening 12 of the bottom of the hopper. The ends of the bars 11 are rounded, and their longitudinal edges are sharpened to provide cutting edges 13 at the front of the blades, as clearly shown in Fig. 70 4 of the drawings. The bar 11 is provided with a central enlargement or longitudinal boss 14, which is recessed to provide a socket 15 for the reception of a wedge-shaped key 16, that secures the bar to the axle. By this 75 construction the bars are rendered detachable and may be readily removed when it is necessary to sharpen them. The arms by being provided with cutting edges are adapted to feed positively the manure or other fertilizer to be distributed, and the said fertilizer is discharged into furrows formed by a plow 17, located in front of the axle. This prevents the fertilizer from being blown away as it is deposited, and it causes the same to 80 mix readily with the soil.

The plow is secured to a standard 18, having its upper ends 19 reduced and pivoted in a socket at the lower face of the rear portion of the draft beam or pole, as clearly indicated 90 in Fig. 2 of the accompanying drawings. The plow by being pivoted in this manner may be readily adjusted to run the desired depth, and it is connected with an operating-lever 20, fulcrumed on a standard 21 at the front 95 of the frame and extending to the rear of the hopper. The front end of the lever 20 is pivoted to a forked connecting-piece 22, which straddles the draft beam or pole and is pivoted to the standard of the plow. This connecting-piece preferably consists of a pair of bars spaced apart by a strip 23 and having their lower portions offset to form the fork. The upper terminals of the bars are extended 100

beyond the spacing-strip and are pivoted to the opposite sides of the front end of the lever. By raising and lowering the rear end of the lever the plow may be raised and lowered and adjusted to any position.

The feed of the fertilizer-distributer is controlled by a slide 24, arranged at the back of the hopper and adapted to extend through a slot 25 thereof. The rear portion of the slide is supported by a transverse bar 26, which connects the rear standards.

The invention has the following advantages: The fertilizer-distributer, which is simple and comparatively inexpensive in construction, is adapted to operate on all kinds of fertilizer and is capable of positively feeding the same and of depositing it in a furrow. The arms, which are provided with cutting edges, are adapted to force the material out of the hopper, and they may be readily thrown into and out of operation by the clutch mechanism when the distributer reaches the end of a row and it is desired to turn it or when it is desired to stop the feed for any other purpose. The feed of the hopper may be regulated, and the plow is capable of ready adjustment to vary its depth in the soil. The bars which form the cutting blades or arms may be readily removed from the axle when it is necessary to sharpen them.

Changes in the form, proportion, size, and the minor details of construction within the scope of the appended claims may be resorted to without departing from the spirit or sacrificing any of the advantages of this invention.

What is claimed is—

1. A fertilizer-distributer comprising a hopper, a shaft or axle provided with an opening, a bar arranged within the opening and projecting from opposite sides of the shaft or axle and having a central socket or recess, and a wedge-shaped key fitting in the socket or recess and securing the bar in the opening of the shaft or axle, substantially as described.

2. In a device of the class described, the combination of a shaft or axle provided with openings, bars passing through the openings, projecting from opposite sides of the shaft or axle and having front cutting edges, and keys securing the bars in the said openings, substantially as described.

In testimony that I claim the foregoing as my own I have hereto affixed my signature in the presence of two witnesses.

IRA L. STELL.
